(57) **CLAIM**

The ornamental design for a shaving razor stand, as shown and described.

DESCRIPTION

FIG. 1 is a front perspective view of a design of a shaving razor stand showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is rear perspective view thereof.

The dash lines shown illustrate portions of the shaving razor stand and form no part of the claimed design. The dash dot lines shown illustrate boundary lines and form no part of the claimed design.

1 Claim, 8 Drawing Sheets
